ABSTRACT OF THE DISCLOSURE

A process for reductively cleaving an aromatic carboxylic acid amide or an aromatic sulfonic acid amide into a corresponding amine and aromatic alcohol or aromatic sulfonic acid, respectively, by electrolyzing a solution of said amide in the presence of a tetraalkyl ammonium salt such as tetramethyl ammonium chloride.

It is already known to split carboxylic acid amides with lithium alanate by way of reduction to form alcohols and amines (J. Org. Chem., 18, 1190). The process can, however, be successfully applied only if acid amides derived from weakly basic amines are concerned, the nitrogen atom of which is coupled with a system capable of exhibiting a strong resonance.

It is likewise known to reduce p-toluenesulfonamides to the corresponding amines by the action of sodium in boiling isoamyl alcohol (Berichte, 86, 1246 (1953)). In this process, the tosyl radical is split into toluene, sulfur dioxide and hydrogen sulfide. The high reaction temperatures and the strongly alkaline medium may, however, unfavorably affect sensitive amines.

Tests for reductively splitting sulfonamides by means of Grignard reagents or by means of lithium-aluminum hydride likewise show unsatisfactory results (Monatshefte, 84, 651 (1953); J. Org. Chem., 16, 952 (1951)).

Now we have found that aromatic carboxylic acid amides and sulfonic acid amides can be split under protective conditions by subjecting them in the presence of tetraalkylammonium salts to electrolytic reduction. The compounds correspond to the general formulae

In the above formulae R represents, for instance, a phenyl group, which may be substituted, or a naphthyl group. R¹ and/or R² represent, for instance, hydrogen, low-molecular weight alkyl, cycloalkyl with 5 to 8 carbon atoms, a phenyl group which may be substituted by low-molecular weight alkyl, a phenylalkyl group or aralkyl groups, or, together, represent an alkyne group having 3 to 8 carbon atoms which may be interrupted by O, N or S. R¹ may likewise be the radical of an amino acid or of a peptide. R may carry further substituents which are not reducible. As such, there are suit-

2

able, in particular, low-molecular weight alkyl, phenyl, trifluoromethyl, low-molecular weight alkoxy, low-molecular weight alkylene-dioxy, carboxy, carbalkoxy, amino and hydroxy groups.

5 The tetraalkyl-ammonium salts used are derived from inorganic acids such as hydrohalic acids, especially hydrochloric and hydrobromic acid, sulfuric acid, phosphoric acid or perchloric acid. Organic acids such as formic acid, acetic acid, propionic acid and higher fatty acids as well as aromatic carboxylic acids, for instance benzoic acids, can likewise be used as salt formers. The tetra-alkyl-ammonium salts contain alkyl groups with up to 4 carbon atoms, preferably tetramethyl-ammonium salts.

10 15 The electrolysis is carried out in a vessel in which the anode and cathode are separated by a diaphragm. As material for the anodes, graphite is preferably used, but boron carbide and other carbides may likewise be used. As cathode material, metals are used, in particular mercury, lead, iron and platinum. As solvent, methanol is generally employed. Water or aqueous solutions of appropriate ethers, such as dioxane or tetrahydrofuran are likewise suitable. In order to ensure a rapid course of the reaction and quantitative yields, it is recommendable

20 25 to add the tetra-alkyl ammonium salt in excess. A proportion of 3 parts of ammonium salt to 1 part of substrate to be split has proved most favorable, but any other proportions may likewise be used with success. The range of the reaction temperature is between 0° and 20° C., preferably between 5 and 10° C. The termination of the reaction is announced by a strong evolution of hydrogen. In order to attain a complete cleavage it is recommended to exceed the theoretically required period by one fourth to one third of the time involved.

30 35 In the process of the present invention, amines and aromatic alcohols or aromatic sulfonic acids are simultaneously obtained in high yields. By-products are not formed in the course of the reaction. A possibility for use is, therefore, in the field of peptide synthesis. Since the peptides formed as decomposition products are not racemized or decomposed because of the gentle reaction conditions, the process permits removal of the carbonyl radicals or of the tosyl group used as protective groups in the peptide synthesis in an uncomplicated manner. Furthermore, the process constitutes a practicable method for the preparative production of aromatic sulfonic acids which, otherwise, are obtained with difficulties only.

10 millimols of the substrate to be split are subjected to electrolysis together with 30 millimols (3.3 grams) of tetramethylammonium chloride in 35 cc. of methanol. Upon cooling of the reaction mixture of +5° C., an earthenware shell containing the graphite anode and cooling finger is introduced into the vessel. The space between the mercury surface and the bottom of the shell amounts to 0.5 to 1 cm. 1-2 cc. of water are introduced into the anode region. As soon as the electric circuit is closed (18-24 volts) the intensity of the current soon increases. It is maintained constant at 1 ampere by means of a variable electrical resistance.

If two vessels are connected in series, 40 volts are applied. From time to time the reaction vessel is slightly

shaken. About 10 minutes after the evolution of hydrogen has set in, the electrolysis is interrupted, the earthenware shell (tube) is rinsed with a small amount of methanol and the reaction batch is worked up.

Generally, the reduction is carried out at a temperature between 5° C. and 10° C. For working up the reaction mixture, 5 cc. of 2 N-sodium hydroxide solution are added and the amino component is extracted with ether. The amine is precipitated from the ethereal solution in the form of the hydrochloride, and the yield is determined. The following table shows an enumeration of the compounds examined and the yields in split products.

Carboxylic acid	Amine	Yield Percent	Alcohol	Yield Percent
N-n-hexylbenzamide	n-Hexylamine	66.0	Benzyl alcohol	68.8

Ts=tosyl.

Splitting of N-p-toluenesulfonyl-L(-)-tyrosine

3.14 grams of N-p-toluenesulfonyl-L(-)-tyrosine are subjected to reductive cleavage as described above. Tyrosine, which is sparingly soluble in methanol, begins to precipitate in the course of the electrolysis. At the end of the electrolysis the product is rinsed with 2 N-sodium hydroxide solution in a separating funnel, mercury is separated off and the clear solution is filtered. This is concentrated to a small volume and acidified by means of 2 N-hydrochloric acid in the cold. Para-toluene-sulfonamide which might not have reacted and the toluene-sulfinic acid are filtered off with suction and from the filtrate the free amino-acid is precipitated by means of sodium bicarbonate. Yield after drying: 1.7 g.=100%.

For purification, the amine is dissolved in 10 cc. of 2 N-hydrochloric acid and precipitated by means of sodium bicarbonate. Yield: 1.6 grams=95.7% of the theory. Determination of the specific rotation with $c=5.6$ grams/10 cc. in a 1 dm. tube in 2 N-hydrochloric acid solution:

$[\alpha]_D^{20}=-10.5$

The pure starting substance shows a rotation value of

$[\alpha]_D^{20}=-11.1$

The small difference in the specific rotation value is due to slight contamination with sodium chloride and sodium bicarbonate. A rotation value of $[\alpha]_D^{20}=-10.5$ is also obtained if the pure starting substance is dissolved in 2 N-hydrochloric acid and precipitated by means of NaHCO_3 .

Splitting of p-toluenesulfonyl-glycyl-glycine

2.43 grams of p-toluenesulfonyl-glycyl-glycine are subjected to splitting. The electrolytic splitting occurs as de-

scribed above for toluenesulfonyl-tyrosine. At the end of the electrolysis the dipeptide again dissolves due to the increasing alkalinity. Sulfinic acid is obtained in a yield of 92.5% of the theory. The alkaline reaction mixture is concentrated nearly to dryness in a rotating evaporator and 40 cc. of absolute alcohol are poured thereon. On

Toluenesulfonamide (tsa)	Amine	Yield, percent	Sulfinic acid	Yield, percent
N-n-hexyl-tsa	n-Hexylamine	93.8	Toluenesulfinic acid	97.3
N-n-butyl-tsa	n-Butylamine	54.8	do	96.6
N-cyclohexyl-tsa	Cyclohexylamine	77.0	do	95.3
N-benzyl-tsa	Benzylamine	64.4	do	90.0
N-phenyl-tsa	Aniline	87.8	do	87.3
N,N-diphenyl-tsa	Diphenylamine	88.3	do	86.0
N-phenyl-N-benzyl-tsa	Benzylaniline	95.5	do	96.6
N-2,6-dimethylphenyl-tsa	2,6-dimethylaniline	92.1	do	94.0
N-2,6-diethylphenyl-tsa	2,6-diethylaniline	94.4	do	94.4

neutralization by means of methanolic hydrochloric acid 45 the diglycine precipitates.

Yield 1.2 g.=91%. In the mother liquor, only slight amounts of diglycine can be detected with the aid of thin-layer chromatography. The precipitate is recrystallized from a mixture of ethanol and water (3:2).

50 *Analysis.*—Calculated for $\text{C}_4\text{H}_8\text{N}_2\text{O}_3$ (132.1): C, 36.36; H, 6.1. Found: C, 36.34; H, 6.57.

Splitting of toluene-sulfonylglycyl-(D,L)-phenyl-alanine

The splitting is carried out as described for N-p-toluenesulfonyl-tyrosine. 10 millimols of toluene-sulfonylglycyl-(D,L)-phenyl-alanine yield 1.8 grams of glycyl-(D,L)-phenyl alanine, i.e. 81% of the theory. The substance is recrystallized in a mixture of alcohol and water (30:17).

55 *Analysis.*—Calculated for $\text{C}_{28}\text{H}_{20}\text{N}_2\text{S}$ (376.38): C, 59.44; H, 6.35. Found: C, 59.31; H, 6.26.

Splitting of N-benzoyl-glycylglycine

The reductive splitting is effected as described for benzamides. From 2.8 grams of N-benzoyl-glycylglycine, 1 gram of pure glycylglycine is obtained (=75.6% of the theory).

65 We claim:

1. A process for reductively cleaving an aromatic carboxylic acid amide or an aromatic sulfonic acid amide into a corresponding amine and aromatic alcohol or aromatic sulfinic acid, respectively, which process comprises electrolyzing a solution of said amide in the presence of a tetraalkyl ammonium salt.

70 2. A process as in claim 1 wherein said tetraalkyl ammonium salt is tetramethyl ammonium chloride.
